(57) **CLAIM**

The ornamental design for a attachable augmented reality display device with USB connector, as shown and described.

DESCRIPTION

FIG. 1 is a perspective view of a attachable augmented reality display device with USB connector showing my new design;

FIG. 2 is a front view of the attachable augmented reality display device with USB connector;

FIG. 3 is a top view of the attachable augmented reality display device with USB connector;

FIG. 4 is a right side view of the attachable augmented reality display device with USB connector;

FIG. 5 is a left side view of the attachable augmented reality display device with USB connector;

FIG. 6 is a rear view of the attachable augmented reality display device with USB connector; and,

FIG. 7 is a bottom view of the attachable augmented reality display device with USB connector.
